UNITED STATES PATENT OFFICE.

JAMES A. FULLER, OF PROVIDENCE, RHODE ISLAND, ASSIGNOR TO THE FIRM OF HAMILTON & HAMILTON, JR., OF PROVIDENCE, RHODE ISLAND.

LOCKET AND SIMILAR ARTICLE.

No. 876,902.

Specification of Letters Patent.

Patented Jan. 14, 1908.

Application filed July 3, 1907. Serial No. 381,985.

To all whom it may concern:

Be it known that I, JAMES A. FULLER, a citizen of the United States, residing at Providence, in the county of Providence and State 5 of Rhode Island, have invented certain new and useful Improvements in Lockets and Similar Articles, of which the following is a specification.

The invention relates to lockets or similar 10 articles of jewelry and more especially to a form of hinge and hinge-mounting adaptable to a locket of the invisible or concealed-joint type. The hinge is of such form and arrangement that the locket when closed may be 15 very thin—a result which is very important in this art.

The invention also provides an improved 20 method of making the hinge and of mounting it in the locket so that it is secured by retaining rings, as will hereinafter appear.

The drawing illustrates an exemplification 25 of the invention.

Figure 1 is a perspective view of the open locket; Fig. 2 a cross section through the 30 hinge with the locket open; Fig. 3 a cross section with the locket closed; Fig. 4 a side view of the hinge removed from the locket; Fig. 5 a section of Fig. 4 taken at one side of the block; Fig. 5^a a view of a blank from which 35 one of the hinged leaves is formed; Fig. 6 a bottom plan of one of the retaining rings, and, Fig. 7 a similar view of the other ring.

Reference numerals 1 and 2 designate the 40 two principal members of the locket which are called arbitrarily the bottom and top, respectively. The hinge, as best seen in Figs. 4, 5 and 5^a, consists of a center block 3 bored through at each end, two leaves 4 which are bent up from a flat blank shown in Fig. 5^a into the form shown in Fig. 4 and two pins 5 passing through the holes in the block and the eyes formed in the leaves. The overlying flat portions of the hinge leaves are commonly simply pressed into position and need 45 not be soldered or otherwise fastened together. The rings 6 shown in Figs. 6 and 7 are made with an outline to conform to the locket members (usually either round or oval) and are shaped on the surfaces which 50 fit into the locket members (the surface presented to the eye in Figs. 6 and 7) so as to fit said members; *i. e.*, in the present instance rounded off at the edges, as seen in cross section in Figs. 2 and 3.

55 For a short portion of their circumference

the rings are cut away from the surface adjoining the locket member, as at 7, to provide a recess for reception of one of the hinge-leaves and also cut away from the edge at the same point providing a recess 8 for the pivot 60 for one of the hinge-eyes and a part of the hinge-block 3. The sharp corners 9 of the ring adjacent to recess 8 are cut away in the ring 6^a, which is intended for the top of the locket, as at 10. This provides clearance 65 for the reception of the edge of the bottom locket member when the locket is open.

In assembling, the complete hinge, as shown in Fig. 4, is connected to the locket members, the bottom of one of the hinge 70 leaves being soldered to the bottom member so that its pin 5 is fairly close to the edge of the member and the bottom of the other leaf being soldered to the top member of the locket so that its pin is further removed from 75 the edge of the member. Ring 6 is then soldered into the bottom hinge member with recess 7 overlying the corresponding hinge-leaf and ring 6^a is soldered in the top member in a similar way. The locket when 80 closed, as in Fig. 3, is to be secured at the point 11 by any suitable catch, not shown, and as will be seen in that figure, the hinge is entirely concealed, the only joint or break in the outside surface being the line of intersection of the two members. To open the 85 locket the catch is released and the members moved apart. Block 3 first turns upon the pin 5 in the bottom member of the locket so that the edge 12 of the top member moves 90 backward until it is clear of the adjoining edge of the bottom. Further opening movement of the locket causes the edge of the bottom member to telescope within that of the top until the parts are in the position shown 95 in Fig. 2. The edge of the bottom member and the corners 9 of the bottom ring under these conditions enter a space formed by the recess 8 and by the cut away portions 10 of the top ring.

100 It is to be noted that while the flat hinge leaf members are not connected together in any way the upper part of the leaf is firmly held under the ring. Any unusual strain on the hinge, therefore, cannot open the locket leaves, since this method of fastening is much stronger than could be provided by soldering or pinning the parts of the leaves together. The block is made solid and the ends of the pins lie between the surfaces forming the 110

limits of recess 7 in the rings so that the pins cannot work out endwise. Locket hinge-leaves have heretofore been made without a double overlying portion, the fixed pivotal 5 sockets for the pins consisting simply of fingers integral with one of the leaves curled around the pin and having no means of fastening. Such hinges are readily forced open by accidentally opening the locket too far, 10 resulting in dismemberment of the joint.

Having described the invention I claim—

1. In a locket or the like, the combination of a top and a bottom member, a hinge comprising two leaves, a block pivoted separately 15 to each leaf, and rings, one secured in each locket member and having recesses accommodating the hinge leaves.
2. A concealed joint locket comprising two locket members, a hinge comprising a block, 20 two pins passing through the block and two leaves each formed of a flat blank with a central aperture, the side members of which are bent around the pins to form pivots and the end members of which lie against each other, 25 one surface of each of the leaves being soldered to one of the locket members, and recessed rings, one overlying each of the leaves and serving to hold the free member of the leaf in position.
3. In a locket, the combination of a top and a bottom member, a hinge comprising two leaves each formed of a flat blank with a central aperture and folded upon itself to provide a pin socket and one of the members 35 of each leaf so formed being secured to one of the locket members, a block, and two pins, one in each end of the block, engaging the sockets formed in the corresponding hinge leaves.
4. A locket comprising two dished mem- 40

bers arranged with their concave faces together, a hinge entirely concealed when the locket is closed and connected to the locket members at different distances from their edges so as to cause the edge of one member 45 to lie within the adjoining edge of the other member when the locket is opened, and rings, one for each member, overlying parts of the hinge and serving to retain the hinge in assembly.

5. A locket comprising two dished members arranged with their concave faces together, a hinge entirely concealed when the locket is closed and connected to the locket members at different distances from their edges so as to cause the edge of one member 55 to lie within the adjoining edge of the other member when the locket is opened, and rings, one for each member, overlying parts of the hinge and serving to retain the hinge in assembly; one of the rings having a portion cut away to accommodate the edge of the opposite locket member when the locket is opened.

6. A locket comprising a central block provided with two projecting pivots, two leaves 65 each consisting of two overlying flat plates connected by integral side members shaped so as to form pivot sockets containing one of the pivots aforesaid and embracing one end of the block, and rings, one secured in each locket member, recessed to accommodate the hinge leaves, overlying the leaves and serving to prevent disassembly of the hinge by the pulling apart of the overlying leaf members.

JAMES A. FULLER.
